The ornamental design for a ribbed augment for a prosthetic implant, as shown and described.

DESCRIPTION

FIG. 1 is an end view of a ribbed augment for a prosthetic implant;

FIG. 2 is a perspective view thereof;

FIG. 3 is a top plan view thereof;

FIG. 4 is a bottom plan view thereof;

FIG. 5 is an end view thereof of the end shown in FIG. 1;

FIG. 6 is an end view thereof of the end opposite the end shown in FIG. 5;

FIG. 7 is a side elevational view thereof; and,

FIG. 8 is a side elevational view thereof of the side opposite the side shown in FIG. 7.

The broken line showing of the tibial plate in FIG. 1 and of the screw holes in FIGS. 2–4 and 8 is for illustrative purposes only and forms no part of the claimed design.
